(57) **CLAIM**

The ornamental design for a communications headset, as shown and described.

DESCRIPTION

FIG. 1 is front-bottom-right perspective view of a communications headset showing my new design;

FIG. 2 is a front view thereof;

FIG. 3 is a back view thereof;

FIG. 4 is a bottom view thereof;

FIG. 5 is a top view thereof;

FIG. 6 is a right side view thereof;

FIG. 7 is a left side view thereof;

FIG. 8 is another top view of FIG. 5 with an ear loop in broken lines;

FIG. 9 is a right side view thereof with the ear loop in broken lines; and,

FIG. 10 is left side view thereof with the ear loop in broken lines.

The broken lines showing of the unclaimed environment forms no part of the claimed design.
